UNITED STATES PATENT OFFICE

ROY KLOMPARENS, OF BOSTON, MASSACHUSETTS

ADJUSTABLE FURNACE REGISTER

Application filed March 27, 1928. Serial No. 265,210.

This invention relates to an adjustable furnace register. The object and purpose of the invention is to provide a register which is adjustable as to size in one direction in order that it may be adjusted to conform to and work with different sizes of register boxes. I have made a companion invention relating to adjustable register boxes which are of a standard length but which may be adjusted to many different widths and the register of the present invention may be used therewith, though of course it is not restricted in any sense to use with adjustable register boxes only.

Different sized rooms in dwellings which are heated by furnaces require different volumes of heat in order to properly heat the same; and the furnace pipes, register boxes and registers through which the air is carried and distributed to a room are likewise of different sizes and have at least approximate relation to the sizes of the rooms which are to be heated. Heretofore it has been thought necessary to carry the several different sizes of registers in stock, using one size of register for one room which is to be heated and another and larger size for a larger room. But with my invention one stock article of furnace register, which is easily adjusted to a desired size, being made larger or smaller as the circumstances require, may be used.

An understanding of the invention and the preferred structural embodiment thereof may be had from the following description taken in connection with the accompanying drawings, in which,

Fig. 1 is a perspective view of the assembled register.

Fig. 2 is a perspective view showing the two parts of the register frame separated, the register damper being mounted on one of said sections.

Fig. 3 illustrates in perspective the register grille which in practice is connected with the frame,

Fig. 4 is an enlarged horizontal section through the register shown in Fig. 1, and,

Fig. 5 is an enlarged vertical section there-

Like reference characters refer to like parts in the different figures of the drawings.

In the construction a register frame is made which consists of upper and lower sections. Both are of sheet metal, the lower frame including a lower horizontal rail of angle form having a front flange 1 and a bottom flange 2, the upper edge portion of the flange 1 being bent backwardly a short distance, as indicated at 3, and thence extending vertically to make a terminal lip 4. The rear edge portion of the horizontal flange 2 is bent back upon itself, as at 5, and two spaced apart slots 6 are cut through the rearwardly bent section 3 described.

The vertical sides are likewise of angle form having front flanges 7 continuous and integral with the flange 1, and rearwardly extending flanges 8. The front flanges 7 at their inner edges are bent inwardly at 9, being continuations of the section 3 previously described, and then are continued inwardly to make the lips 10 which lie in the same vertical plane with the lip 4. Each of the rearwardly extending flanges 8 at its rear edge is bent backwardly upon itself in U-form to provide a guide 11 which is spaced a short distance from the inner side of the flange 8 with which it is connected.

The upper section of the register frame is likewise of sheet metal and has an upper rail of angle form with a front vertical flange 12 and a rearwardly or inwardly extending horizontal upper flange 13. Said flange 12 at its lower edge is bent inwardly making the section 14 corresponding to the section 3 on the lower rail 1 and thence continuing in a downwardly extending vertical lip 15. The vertical sides of the upper section are of angle form having front face flanges 16 and rearwardly extending flanges 17, the front flanges 16 being bent inwardly and then continued as inwardly extending lips 18. The corners where the lips 15 and 18 come together are widened and made into supporting members 19, the purpose of which will later appear. The rear edge of the upper flange 13 is bent back upon itself as indicated at 20 similar to the bent part 5 of the horizontal flange 2 of the lower rail.

It is evident that the upper section may have an adjustable telescoping connection or attachment to the lower section. The flanges 16 are slightly less in width than the flanges 7 and fit between the sides 8 and the parts 9 while the rear edge portions of the flanges 17 are received in the guides 11. The frame accordingly may be adjusted as to height to many different positions.

Within the frame a register grille is mounted. This grille likewise is formed of two adjustable parts or sections made of sheet metal. The lower section has a horizontal rail 21 from which a plurality of spaced apart vertical fingers 22 extend upwardly. The fingers 22 are all substantially half round shape but at their edges are turned inwardly to make guide lips 23. The lower rail 21 at its lower side is provided with two spaced apart downwardly extending tangs 24 located so as to be freely received within the slots 6 previously described.

The upper section of the grille is of similar formation having an upper rail 25 and downwardly extending fingers 26 of smaller size than the fingers 22 so that they may telescope therein. Substantially midway between the sides and the upper end of the upper section a cross member 27 connects certain of the fingers, thereby leaving an open space above the member 27 for a hereinafter described purpose. The two sections when placed together are readily adjusted as to height to many different sizes and it is evident that the retaining guide lips 23 on the fingers 22 serve to prevent detachment of the two sections of the grille.

A register damper plate is mounted for swinging movement on the upper section of the frame. The damper is made of an upper horizontal rod 28 around which the upper edge of a damper plate 29 is bent to make a secure and permanent connection. The ends of the rod 28 are free to receive substantially U-shaped clips 30 around them which lie back of the supporting members 19 and are connected thereto by stove bolts 31, serving not only to support the damper plate 29 but to frictionally mount the rod 28 whereby the damper plate will normally remain in any position to which it is swung.

When the register is to be assembled to fit any desired size of register box or opening in the wall the two sections of the frame are telescoped together and adjusted to the proper size. The two sections of the grille are likewise telescoped and adjusted to size and the tangs 24 passed through the openings 6 and the grille brought against the front sides of the inwardly extended lips 4, 10, 15 and 18 of the frame sections. Clips 32 (see Fig. 5) at their upper ends are fastened to the face 12 of the upper rail and extend downwardly over the upper rail 25 of the grille

thereby securing the grille and frame together.

A finger hold 33 is fastened to the front side of the damper plate 29 in such a position that it extends through the opening in the grille above the member 27 as shown in Fig. 1. In practice the damper plate 29 is made with a length sufficient to take care of the largest size of register which will be used and for the smaller sizes it is merely necessary for the one installing the furnace to cut away any required portion of the lower end of the plate 29 on a horizontal line, a plurality of which are indicated at 34 in Fig. 2.

It is evident from the foregoing that a register and grille therefor together with the necessary damper plate may be made as a stock article which is universally adapted for all of the different sizes of registers used in installing a furnace in a dwelling or other building. An invention of this kind is of considerable value, greatly reducing the number of stock parts required and making it necessary merely for the furnace company to ship a required number of registers to a place of installation without regard to the size thereof, as any register made in accordance with my invention will fit any register box or opening made in the wall or floor where a furnace is to be installed. The invention is defined in the appended claims and is to be considered comprehensive of all forms of structure coming within their scope.

I claim:

1. In a construction of the class described, a register frame comprising upper and lower sections of sheet metal, the lower section having a lower rail of angle form and two integral upwardly extending end portions also of angle form, one flange of each of said lower rail and said end portions lying in the same vertical plane at the front of the frame and other flanges of the said end portions of said section extending rearwardly therefrom, each at its rear edge being turned inwardly back upon itself to provide a U-shaped guide, and the inner edge portions of said front flanges being first pressed rearwardly and then extending inwardly to provide terminal lips, the upper section of said frame having an upper rail and depending side portions of sheet metal, also of channel form and likewise formed at the inner edge portions of the front flanges thereof with rearwardly pressed portions terminating in inwardly extending lips, said side portions of the upper sections being telescopingly received within said side portions of the lower sections to provide an adjustable frame adjustable to different dimensions as to the height thereof.

2. A construction containing the elements defined in claim 1, each of said inwardly extending lips at the corners of said upper section being enlarged to provide supports, a

rod extending horizontally back of said supports, clips passed around said rod and having ends lying immediately back of said supports, bolts passing through said clips and supports for clamping the same on the rod 5 and a damper plate secured to and depending from said rod back of the frame.

3. A construction containing the elements in combination defined in claim 1, combined 10 with a grille comprising two sections having telescoping connection with respect to each other whereby the same may be adjusted as to height to lie across the opening in the frame and against said inwardly extending 15 terminal lips, spaced apart tangs extending downwardly from the lower side of the grille, said horizontal member of the lower section of the frame having spaced apart openings to receive said tangs, and clips attached to the upper horizontal member of 20 the upper section of the frame extending over and bearing against said grille at its upper end.

In testimony whereof I affix my signature.
ROY KLOMPARENS.
